EDWARD E. STEVENSON, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA

SUCKER-ROD ELEVATOR

Application filed May 14, 1932. Serial No. 611,345.

My invention relates to supporting devices for linear members, and more particularly to supporting devices for sucker-rod elevators.

5 The pumping equipment ordinarily used in pumping a deep oil well consists of a pump suspended in a well on a pump tubing, this tubing being in turn suspended from the surface of the ground. The pump is equipped 10 with a plunger which is connected to a string of sucker-rods extending upward through the pump tubing, the upper end of the string of sucker-rods being attached to a walking-beam suitably driven to reciprocate the pump 15 plunger.

This string of sucker-rods is formed of lengths having enlarged heads at either end thereof and these lengths are joined together by suitable couplings. In raising the string 20 of sucker-rods from the well, it is necessary to employ a device for suitably grasping the upper end of the string at the surface of the ground.

25 In a sucker-rod elevator of this character, it is important that the device be quickly and easily attached to and detached from the sucker-rod, and be positively locked when in gripping position to obviate the possibility of lacing a string of sucker-rods while withdrawing the sucker-rods from the well.

It is, therefore, an object of my invention to provide a device which will grasp and support sucker-rods, although I do not wish to limit the scope of my invention to a device for 35 supporting sucker-rods in oil wells, as my invention is equally applicable to supporting pipe, etc.

Another object of my invention is to provide a sucker-rod supporting device embodying a rod-grasping mechanism which automatically closes when a sucker-rod is moved into position to be engaged thereby.

A still further object of my invention is to provide a device of the character described 45 which embodies a locking mechanism for normally holding the rod-grasping mechanism in an open rod-receptive position and which is released by engagement with a sucker-rod when such rod is positioned within the rod-grasping mechanism.

It is still another object of my invention to provide a rod-supporting device in which the rod-grasping and supporting mechanism is positively held in closed position while the rod is supported therein.

55 Further objects and advantages of my invention will be apparent from a perusal of the following specification, the accompanying drawings, and the appended claims.

Referring to the drawings, which are for 60 illustrative purposes only:

Fig. 1 is a partially sectioned front elevational view of my device showing the rod-grasping members in closed position.

Fig. 2 is a view comparable to Fig. 1 but 65 showing the rod-grasping members locked in open position.

Figs. 3 and 4 are top plan views of Figs. 1 and 2 respectively, with parts broken away.

Fig. 5 is a side elevational view taken as 70 indicated by the arrow 5 of Fig. 1.

Fig. 6 is a perspective view of one of the rod-grasping closure members of my invention.

Fig. 7 is a perspective view of the closure 75 member operating sleeve of my invention.

In the drawings I show an elevator body 11 which is substantially frusto-conical in shape. The body 11 has a base flange 12 and is provided adjacent the top thereof with bosses 13 adapted to receive bail pivoting pins 14. The bosses 13 are offset forwardly relative to the vertical axis A—A of the body 11 and are placed diametrically opposite relative to the axis B—B of the body 11, as shown in Fig. 3. Adjacent the bosses 13, the body 11 is provided with a pair of bail stop lugs 15 which project outwardly therefrom. The stop lugs 15 are offset rearwardly from the vertical axis A—A of the body 11 and are in substantially the same horizontal plane with the bosses 13 and the pins 14. The lugs 15 are also placed diametrically opposite relative to the axis B—B of the body 11.

95 Pivoted to the body 11 by the pins 14 is a bail member 16, the upper end of which (not shown) is adapted to be engaged by a suitable supporting means. The lower end of each leg of the bail member 16 is provided 100 with a bore 19 through which the pins 14 ex-

tend into the bosses 13 in threaded engagement therewith, and is enlarged to form a recess 20 for the reception of the lugs 15, the configuration of the recess 20 being such that 5 it allows the bail member 16 to pivot on the pins 14 in one direction, as indicated by the arrow 21 of Fig. 5, but prevents rotation thereof relative to the body 11, in a direction opposite to that indicated by the arrow 21, 10 beyond a point which is parallel to the vertical axis C—C of the pins 14, as shown in Fig. 5. It will be seen that due to the center of gravity of the body 11 being located rearwardly of the axis C—C of the pins 14, the 15 body 11 will always assume the correct rod-receptive position when supported by the bail member 16.

The body 11 is provided with an opening 30, 20 extending vertically therethrough. The opening 30 is conoidal in configuration, being of an elliptical shape at the top of the body 11 as indicated at 31, and extending convergently downward, is of circular configuration at the bottom thereof, as indicated at 32.

Provided in the walls forming the opening 30 is a pair of inwardly facing cam grooves 35 and 36. The cam grooves 35 and 36 are positioned diametrically opposite within the opening 30 and converge downwardly from 30 enlarged openings 37 and 38 at the top of the body 11, to a point coincident with the periphery of the bottom 32 of the opening 30.

Formed in the front of the body 11 is a 35 gate or rod passage 40 which is of substantially the width of the bottom 32 of the opening 30, and communicates with the opening 30 throughout the length thereof.

Slidably positioned within the opening 30 in a manner adapted to close the passage 40, 40 is a pair of rod-grasping closure members 41 and 42. The members 41 and 42 are provided with tongues 43 and 44 respectively, which tongues conform to the configuration of the cam grooves 35 and 36 respectively, and are 45 adapted to be slidable upwardly and downwardly therein. Each of the closure members 41 and 42 comprises a body 45 having an enlarged semi-elliptical top 46, a downwardly converging outer surface 47 and a perpendicular face 48. Formed in the face 48 of each of the closure members 41 and 42 is a semi-cylindrical slot 50. As will be seen from an inspection of the drawings, the closure members 41 and 42, when placed within the opening 30 with their respective tongues 43 and 44 positioned in the cam grooves 35 and 36 55 and with their respective faces 48 and slots 50 adjacent, cooperate to grasp and support a sucker-rod 51 in the manner indicated by 60 dotted lines in Fig. 1.

Partially surrounding the body 11 is an incomplete sleeve member 55. The sleeve member 55 is shaped to conform to the configuration of the exterior of the body 11 and is 65 adapted to be rotatable relative thereto. Pro-

vided in the sleeve member 55 are two cam slots 56 and 57 having inclined surfaces 58 and 59. Threadably secured to the closure members 41 and 42 respectively, and extending outwardly therefrom and at right angles thereto, are cam following pins 60 and 61. Provided in the body 11 are slots 65 and 66 through which the pins 60 and 61 respectively extend, the outer ends of the cam following pins being engageably received in the cam slots 56 and 57 respectively. 70 75

Partially surrounding the body 11 is a tension spring 70, one end of which is fixed to the flange portion 12 of the body 11 by screw means 71, as shown in Fig. 2, and the other end of which is attached to the sleeve 55 by screw means 72, as shown in Fig. 5. As will be clearly seen the spring exerts a force upon the sleeve 55 in the direction of the arrow 80 of Fig. 4, which force normally allows the pins 60 and 61 to rest in the bottom of the inclined cam slots 56 and 57. 80 85

Extending horizontally through the wall of the body 11 diametrically opposite the passage 40 is a bore 85, this bore 85 being closed at its outer end by a threaded plug 86 and communicating with the opening 30 at its inner end 87. The inner end 87 of the bore 85 is of reduced diameter to form a stop shoulder 88. Slidably positioned within the bore 85 is a locking bar 89 having a conical outer end 90 and an enlarged diameter inner end which forms a flange 91 adapted to engage the stop shoulder 88 when the locking bar 89 is in an extreme outer position, as shown in Fig. 4. The locking bar 89 is constantly forced toward its outermost position by a coil spring 92 compressed between the plug 86 and the inner end of the bar 89. The threaded plug 86 is screwed into the bore 85 a sufficient distance so that it does not form a frictional obstruction to the free rotation of the sleeve 55 relative to the body 11. 90 95 100

The operation of my invention is as follows: 110

With the closure members 41 and 42 in their uppermost or open position, as shown in Fig. 2, in which position the closure members 41 and 42 are held against downward and inward movement by contact with the locking bar 89, which is forced outwardly by the spring 92 between the perpendicular faces 48 of the closure members 41 and 42, the sucker-rod 51 is moved into the opening 30 through the passage 40, as indicated by the arrow 95 of Fig. 4. 115 120

When the rod 51 contacts the outer end of the locking bar 89 movement is imparted thereto in the direction of the arrow 98 of Fig. 4 a sufficient distance so that the cylindrical portion 99 of the bar 89 clears the perpendicular faces 48 of the members 41 and 42, whereupon the closure members 41 and 42 are free to move downwardly, and the locking bar 89 is forced entirely within the 125 130 135

bore 85 by a camming action between the perpendicular faces 48 of the members 41 and 42 and the conical portion 90 of the bar 89.

5 It will be clearly seen that as the members 41 and 42 are moved downwardly subject to the force of the tension spring 70 which rotates the sleeve 55 relative to the body 11 in the direction of the arrow 80, allowing 10 the pins 14 to drop toward the lower ends of the slots 56 and 57, the semi-cylindrical slots 50 of the respective members 41 and 42 co-operate to form a substantially cylindrical rod opening 100 which receives the rod 51 15 in the manner shown in Fig. 1.

The weight of a sucker-rod or string of sucker-rods is supported by the upper faces of the members 41 and 42 through engagement with the head of a sucker-rod, as indicated at 101, Fig. 1, and gravitational force imparted by the weight of the rods in the direction of the arrow 102 of Fig. 1 will positively prevent upward movement of the members 41 and 42 and a consequent inadvertent release of the sucker-rod.

When the weight of the rods is removed from the members 41 and 42 by sliding the body downward away from the head of the sucker-rod, the sleeve 55 may be manually 30 rotated relative to the body 11 in the direction of the arrow 104 of Fig. 4, which causes the inclined surfaces 58 and 59 of the respective cam slots 56 and 57 to lift the pins 60 and 61 and consequently the members 41 35 and 42 upwardly. The sleeve 55 is provided with an outwardly projecting finger 105 provided as a grasping means for the manual manipulation of this sleeve. When the extreme upward travel of the members 41 and 40 42 has been accomplished, the locking bar 89 will be forced outwardly between the perpendicular faces 48 of the members 41 and 42, and hold these members in open position until again released by a sucker-rod being 45 positioned in the opening 30.

Although I have herein shown and described but a single embodiment of my invention, it should be understood that I am aware of various features that might be 50 added, and numerous embodiments thereof that might be devised by those skilled in the art without departing from the spirit and scope of my invention.

I claim as my invention:

55 1. In a sucker-rod elevator of the type described, the combination of: a body having an opening therein, said opening being adapted to receive a sucker-rod; walls forming a passage in said body communicating with 60 said opening, said passage being adapted to accommodate the passage of said sucker-rod into said opening; a closure mechanism operable to close said passage; locking means operable to releasably retain said closure 65 mechanism in open position, said locking

means being adapted to be released by contact with said sucker-rod when said sucker-rod is positioned in said opening; automatic means adapted to operate said mechanism to close said passage when said locking means is released; and manual means for operating said mechanism to open said passage. 70

2. In a sucker-rod elevator of the type described, the combination of: a body having an opening therein; walls forming a passage in said body, said passage communicating with said opening; a closure mechanism positioned within said opening, and operable to close said passage; locking means operable to releasably retain said closure mechanism in open position, said locking means being adapted to be released by contact with said sucker-rod when said sucker-rod is positioned in said opening; automatic means adapted to operate said mechanism to close said passage when said locking means is released; and manual means for operating said mechanism to open said passage. 75

3. In a sucker-rod elevator of the type described, the combination of: a body having an opening therein, said opening being adapted to receive a sucker-rod; walls forming a passage in said body communicating with said opening, said passage being adapted to accommodate the passage of said sucker-rod into said opening; a closure mechanism positioned within said opening, and operable to close said passage; locking means operable to releasably retain said closure mechanism in open position, said locking means being adapted to be released by contact with said sucker-rod when said sucker-rod is positioned in said opening; automatic means adapted to operate said mechanism to close said passage when said locking means is released; and manual means for operating said mechanism to open said passage. 90

4. In a sucker-rod elevator of the type described: an elevator body having walls forming a vertically extending opening therethrough, said walls being formed to provide diametrically disposed cam surfaces, said cam surfaces sloping obliquely upward and outward; a vertically extending passage formed in said body, said passage communicating with said opening; a pair of closure members positioned within said opening in movable contact with said cam surfaces, said closure members being adapted to close said

110 passage when in a lowered position, and to open said passage when in an upper position; an inwardly facing channel in each of said closure members, said channels cooperating to form a rod opening adapted to receive a sucker-rod; means for manually moving said closure members upwardly relative to said cam surfaces to open said passage; locking means operable to releasably retain said closure members in an open position, said locking means being adapted to be released by 115 120 125 130

contact with said sucker-rod when said sucker-rod is positioned in said rod opening; and automatic means operably associated with said closure members to move said closure members downwardly to close said passage when said locking means is released.

5. In a sucker-rod elevator of the type described: an elevator body having walls forming a vertically extending opening therethrough, said walls being formed to provide diametrically disposed cam surfaces, said cam surfaces sloping obliquely upward and outward; a vertically extending passage formed in said body, said passage communicating with said opening; a pair of closure members positioned within said opening in movable contact with said cam surfaces, said closure members being adapted to close said passage when in a lowered position, and to open said passage when in an upper position; an inwardly facing channel in each of said closure members, said channels cooperating to form a rod opening adapted to receive a sucker-rod; a closure-operating member in the form of an incomplete sleeve, said sleeve being mounted upon the exterior of said body in such a manner as not to obstruct said passage, and being rotatable relative to said body; a pair of cam slots in said sleeve; a slot formed in said body adjacent each of said cam slots; a pin extending outwardly from each of said closure members, through said slots in said body, said pins being engageably received by said cam slots in such a manner that a rotation of said sleeve in one direction relative to said body will cause said closure members to be moved upwardly on said cam surfaces to open said passage; locking means operable to releasably retain said closure members in an open position, said locking means being adapted to be released by contact with said sucker-rod when said sucker-rod is positioned in said rod opening; and automatic means operably associated with said closure members to move said closure members downwardly to close said passage when said locking means is released.

6. In a sucker-rod elevator of the type described: an elevator body having walls forming a vertically extending opening therethrough, said walls being formed to provide diametrically disposed cam surfaces, said cam surfaces sloping obliquely upward and outward; a vertically extending passage formed in said body, said passage communicating with said opening; a pair of closure members positioned within said opening in movable contact with said cam surfaces, said closure members being adapted to close said passage when in a lowered position, and to open said passage when in an upper position; an inwardly facing channel in each of said closure members, said channels cooperating to form a rod opening adapted to receive a sucker-rod; means for manually moving said closure

members upwardly relative to said cam surfaces to open said passage; a recess formed in said body, said recess communicating with said opening; a locking bar slidably positioned in said recess; resilient means provided within said recess, said resilient means being associated with said locking bar to cause said bar to project outwardly into said opening between said closure members to hold said closure members in an open position by frictional engagement, said locking bar being adapted to be depressed into said recess and out of engagement with said closure members by contact with said sucker-rod when said sucker-rod is positioned in said rod opening; and automatic means operably associated with said closure members to move said closure members downwardly to close said passage when said locking means is released.

7. In a sucker-rod elevator of the type described: an elevator body having walls forming a vertically extending opening therethrough, said walls being formed to provide diametrically disposed cam surfaces, said cam surfaces sloping obliquely upward and outward; a vertically extending passage formed in said body, said passage communicating with said opening; a pair of closure members positioned within said opening in movable contact with said cam surfaces, said closure members being adapted to close said passage when in a lowered position, and to open said passage when in an upper position; an inwardly facing channel in each of said closure members, said channels cooperating to form a rod opening adapted to receive a sucker-rod; a closure-operating member in the form of an incomplete sleeve, said sleeve being mounted upon the exterior of said body in such a manner as not to obstruct said passage, and being rotatable relative to said body; a pair of cam slots in said sleeve; a slot formed in said body adjacent each of said cam slots; a pin extending outwardly from each of said closure members, through said slots in said body, said pins being engageably received by said cam slots in such a manner that a rotation of said sleeve in one direction relative to said body will cause said closure members to be moved upwardly on said cam surfaces to open said passage; locking means operable to releasably retain said closure members in an open position, said locking means being adapted to be released by contact with said sucker-rod when said sucker-rod is positioned in said rod opening; and resilient means operably associated with said sleeve and said body for causing said sleeve to be rotated in an opposite direction when said locking means is released, whereby said closure members will be moved downwardly on said cam surfaces to close said passage.

8. In a sucker-rod elevator of the type described: an elevator body having walls form-

ing a vertically extending opening therethrough, said walls being formed to provide diametrically disposed cam surfaces, said cam surfaces sloping obliquely upward and outward; a vertically extending passage formed in said body, said passage communicating with said opening; a pair of closure members positioned within said opening in movable contact with said cam surfaces, said closure members being adapted to close said passage when in a lowered position, and to open said passage when in an upper position; an inwardly facing channel in each of said closure members, said channels cooperating to form a rod opening adapted to receive a sucker-rod; means for manually moving said closure members upwardly relative to said cam surfaces to open said passage; a recess formed in said body, said recess communicating with said opening; a locking bar slidably positioned in said recess; resilient means provided within said recess, said resilient means being associated with said locking bar to cause said bar to project outwardly into said opening between said closure members to hold said closure members in an open position by frictional engagement, said locking bar being adapted to be depressed into said recess and out of engagement with said closure members by contact with said sucker-rod when said sucker-rod is positioned in said rod opening; and resilient means operably associated with said sleeve and said body for causing said sleeve to be rotated in an opposite direction when said locking means is released, whereby said closure members will be moved downwardly on said cam surfaces to close said passage.

9. In a sucker-rod elevator, the combination of: a body having an opening formed therein; sucker-rod engaging means in said opening and operable between engaged and non-engaged positions; lock means for locking said sucker-rod engaging means in non-engaged position, said lock means being operated by said sucker-rod when same is positioned in said opening; and operating means adapted to move said sucker-rod engaging means into engaged position after said sucker-rod has been placed in said opening and said lock means operated.

10. A combination as defined in claim 9 in which said sucker-rod engaging means includes a plurality of sucker-rod engaging members, and in which said lock means includes a lock member which extends between said sucker-rod engaging members.

In testimony whereof, I have hereunto set my hand at Los Angeles, California, this 11 day of April, 1932.

EDWARD E. STEVENSON.
